PANEL.

No. 20,446.

Patented Jan. 6, 1891.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,448, dated January 6, 1891.

Application filed November 29, 1890. Serial No. 373,074. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, showing my said design and forming part hereof.

My design consists in the rectangular elevation A, from the center B of which channels C extend to the edges of said elevation. The edges of the elevation A and of the chan-

nels C are inclined. The triangular elevations which appear between the channels C have their apexes meeting at the central point B of the panel. The channels C are arranged in groups, as C' C² C³ C⁴ C⁵.

I claim—

The design for a panel, substantially as herein shown and described.

ALLAN B. CAMERON.
